UNITED STATES PATENT OFFICE.

NICHOLAS SLINGLAND, OF FALLS VILLAGE, CONNECTICUT.

WINDOW-SHADE FIXTURE.

SPECIFICATION forming part of Letters Patent No. 296,473, dated April 8, 1884.

Application filed February 23, 1884. (No model.)

To all whom it may concern:

Be it known that I, NICHOLAS SLINGLAND, of Falls Village, in the county of Litchfield and State of Connecticut, have invented a new 5 Improvement in Window-Shade Fixtures; and I do hereby declare the following, when taken in connection with accompanying drawings and the letters of reference marked thereon, to be a full, clear, and exact description of 10 the same, and which said drawings constitute part of this specification, and represent, in—

Figure 1, a sectional front view; Fig. 2, a vertical section enlarged; Fig. 3, a transverse section of one jamb, enlarged; Figs. 4 and 5, 15 modifications.

This invention relates to an improvement in window-shade fixtures, with special reference to railway-cars and like purposes where it is desirable to hold the lower end of the 20 shade to prevent its flapping. A common method of thus holding the shade in railway-cars is to construct each jamb with a notched groove and extend the slat in the bottom of the shade into each of those grooves, and so 25 as to run free in the groove, except when thrown into engagement with one of the notches. The shade being arranged upon a spring-roller at the top draws the slat up against the notches, and so that, the shade being pulled down to 30 engage with any given notch, the upward pull of the spring-roller will hold it in connection with that notch, and to release it therefrom the slat must be taken from the notches, and then it is free to run up through the grooves. 35 In this construction the slat is liable to be misplaced by those inexperienced with its use. The shade can only be held at certain predetermined points, and hence the notches must be made near together or the adjustment of 40 the shade will not often meet the requirements of passengers.

The object of my invention is to overcome these difficulties and provide a device whereby the shade may be held at any desired position, and which will not be liable to disarrangement; and it consists in constructing the jambs with vertical grooves or ribs, combined with a shoe for each of said ribs or grooves, the slat extending from the shoe on one side 45 to the shoe on the other side, with an elastic force applied, the tendency of which is to press the shoes against their respective jambs

with friction sufficient to hold the slat against the upward tendency of the spring-roll, but yield for an easy up or down movement of the 55 shade, and as more fully hereinafter described.

A represents one jamb, and B the other, of a common car-window frame. At the top the shade-roller C is arranged and provided with the usual spring, whereby the shade D will be 60 automatically rolled thereon if left free, the spring of the roller yielding as the shade is drawn downward, which construction of roller is too well known to require particular description in this specification, further than to 65 say that any of the automatic cylindrical shade-rollers now in common use may be employed. In each of the jambs A B a vertical groove, E, is made. These grooves are straight, and their sides parallel. Into each of the grooves 70 E a shoe, F, is set. These shoes fit their grooves so as to move freely therein. Each of the shoes is constructed with a socket, G, into which the respective ends of the slat H will set, as seen in Fig. 2. At one or both 75 ends a spring, I, is arranged to bear between the shoe and the slat, (here represented as in one socket only,) and a spiral spring to bear against the end of the slat. The shade is attached to the slat in the usual manner. The 80 power of the spring I forcing the shoes against their respective jambs will produce sufficient friction to overcome the power of the spring in the shade-roller, and so as to hold the shade at any point of elevation. To raise the shade 85 it is only necessary to apply the hand to the slat and lift slightly. The shoes move upward through their respective grooves, and the shade is rolled up by the spring-roller; or to draw it down, simply take hold of the lower 90 edge of the shade, or pull down upon it, the shoes sliding down freely through their grooves.

The operation of adjusting the shade—that is, pulling down or raising up—is so simple 95 that the most inexperienced person will readily understand the operation necessary to adjust the shade. The spring yields to any irregularities which may from time to time occur in the jambs, and the shade is easily 100 adjusted to any point and held at that point.

Instead of the groove, as seen in Fig. 3, there may be a rib on the jamb, as seen in Fig. 4. In that case the shoe will be grooved.

Instead of constructing the shoe rigid and applying a spring between it and the jamb, the shoe itself may be made in the form of a half-elliptic spring, as seen in Fig. 5, the 5 socket G to receive the end of the slat fitted upon its back. In this case the spring takes its bearing in the grooves at the ends, and is free between for the necessary spring movement.

I claim—

- 10 1. The combination of vertical parallel guides on the jambs of a window-frame, a spring-roll arranged to automatically roll up the shade, a slat in the lower end of the shade, and a shoe arranged upon each of the guides on 15 said jambs, the said slat extending from the shoe on one side to the shoe on the opposite side, and engaged with the respective shoes, the bearing of the said shoes upon the jambs made elastic, substantially as described.

2. The combination of vertical guides on 20 the respective jambs of a window-frame, an automatic shade-roller, a shade attached thereto, a shoe fitted to move up and down on the guide of each of said jambs, a slat at the lower end of the shade, one end resting in a socket 25 on one of the shoes and extending across into a socket on the shoe at the opposite side, and a spring introduced between the shoes and slat, whereby a yielding pressure is produced upon said shoes against their respective jambs, 30 substantially as described.

NICHOLAS SLINGLAND.
